DESIGN FOR A HAIR CLIPPER CASING

Mathew Andis, Racine, Wis.

Application July 19, 1941, Serial No. 102,302

Term of patent 14 years

To all whom it may concern:

Be it known that I, Mathew Andis, a citizen of the United States, residing at Racine, in the county of Racine, and State of Wisconsin, have invented a new, original, and ornamental Design for a Hair Clipper Casing, of which the following is a specification, reference being had to the accompanying drawing, forming part thereof.

In the drawing:

I claim:

The ornamental design for a hair clipper casing, as shown.

MATHEW ANDIS.
